UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

GALLEY MECHANISM FOR TYPE-COMPOSING MACHINES.

1,149,197.

Specification of Letters Patent. Patented Aug. 10, 1915.

Application filed March 12, 1914. Serial No. 824,283.

To all whom it may concern:

Be it known that I, MAURITZ C. INDAHL, a citizen of the United States, residing at Philadelphia, in the county of Philadelphia and State of Pennsylvania, have invented 5 certain new and useful Improvements in Galley Mechanism for Type-Composing Machines; and I do hereby declare the following to be a full, clear, and exact description of the same, reference being had to the accompanying drawings, forming part of this specification, and to the figures and letters of reference marked thereon.

This invention relates to the class of galley mechanisms in which the type support 15 traversing the line assembling channel is automatically returned to initial position near the entrance to said channel by a member reciprocating in a predetermined limited 20 path, and it has for its principal object to increase the capacity of said mechanism so as to render the same automatically operative upon lines in excess of the dimensions indicated by the position of said type support 25 members.

The class referred to is exemplified in Patent No. 674,375, dated May 21, 1901, wherein the type support returning member or arm is yieldingly and movably connected 30 to its support, so that when longer lines than indicated by the maximum movement of said support are to be assembled, the type support will be permitted to pass beyond its returning arm, thus rendering the latter 35 inoperative to perform its function.

The present invention is specially designed to preserve the automatic action of the type support return devices when assembling lines longer than indicated by the 40 throw of the returning member, and this is accomplished by the addition of an auxiliary return mechanism or device which when the indicated length is exceeded, is brought into action to automatically place 45 the type support within the sphere of action of the normal return device or mechanism so that the latter may operate as usual in effecting the final return of the type support in timed relation with the other performing members.

In the accompanying drawings illustrating a preferred form of embodiment of said invention: Figure 1 is a top plan view of a galley mechanism with the invention

applied thereto. Fig. 2 is a partial plan view showing the principal and auxiliary return devices. Fig. 3 is a similar view with the line transerrer in advanced position. Fig. 4 is a partial perspective of the primary and auxiliary return mechanism. 60 Fig. 5 is a perspective of the link supporting the engaging arm of the primary return devices. Fig. 6 is a perspective of the slide for supporting and carrying the engaging arm of the primary return devices. Fig. 7 65 is a perspective of the type support and the engaging slide of the auxiliary return devices.

The same numerals designate like parts in the several figures. 70

For purposes of illustration the invention is shown as adapted and applied to the galley mechanism of the aforesaid Patent No. 674,375, whereof the type assembling channel 1 is composed in part by opposed galley 75 blade 2 and line transerrer 3, the one vertically movable to uncover the galley entrance 4, and the other laterally movable to transfer the assembled line through the galley entrance while the galley blade is withdrawn therefrom as indicated in Fig. 3.

The type for each line are assembled one at a time in the channel 1 and the entering end of the line is upheld by a type support 5 frictionally supported to move longitudinally of the channel upon line transerrer 3. 85

When the line is completed by the addition of the last type, it is engaged by the line carrier 6 movable longitudinally of the type channel, the motion of said carrier terminating with its engaging surface at the inner edge or side of the galley entrance so as to cause the inner end of the line to register therewith. If the line is of standard dimensions its outer end registers with the inner edge of the trip mechanism 7 located at the outer edge or side of the galley entrance; but if the line is too long or too short either the type or the type support will contact with the trip mechanism upon the advance of the line transerrer, and operate to stop the driving mechanism of the machine. After a line has been discharged into the galley, the type support must be returned to a point at or near the entrance to the type 100 channel, to sustain the succeeding line, and this is accomplished in the machine of the prior patent by a return latch 8 pivotally

mounted upon a slide 9, the latter movable, in guides, longitudinally of the type channel with the point or engaging end of the latch intersecting said channel at a point outside 5 of or beyond the type support. The actuating lever 10 for the return latch 8 and line carrier 6 is coupled directly with slide 9, and the latter is in turn coupled through a lost motion connection with line carrier 6, the arrangement being such that when the 10 line is completed an outward motion is transmitted to slide 9 to further withdraw latch 8 from the type support, move line carrier 6 in rear of the last type of the line, 15 and advance said carrier until the inner end of the line registers with the inner wall of the galley entrance. The motion of these parts is then arrested, while galley blade 2 is elevated and line transerrer 3 advanced, 20 after which the motion of slide 9 is reversed, to first withdraw carrier 6 from the type channel, and then return it to the entrance end thereof, at the same time moving latch 8 into contact with type support 5 and returning the latter toward the entrance end 25 of the channel, after which slide 9 is moved outward a short distance to release the type support, when the entire galley mechanism is automatically disconnected from its driving mechanism and brought to rest and so 30 remains during the assembling of the next succeeding line of type.

The position occupied by the return latch 8 in its relation to type support 5 determines the maximum length of line that can be automatically disposed of by the machine, and while the limit may be extended, at the expense of speed, in practice commercial machines are equipped for a maximum capacity 35 of 42 pica for automatic action and 60 pica for semiautomatic action, this latter capacity being obtained by employing a movable or yielding return latch 8 so that when the normal automatic capacity is exceeded the type support may displace the latch and be carried beyond it. In such a case, it is obvious, the capacity of the latch 8 to effect the return of the type support is suspended because said support has been removed beyond the sphere of action of said latch, hence it becomes necessary to return 50 the type support wholly or partly by hand.

The mechanism thus far described is that of Patent No. 674,375, to which reference is had for a more detailed description, and the present improvement as applied thereto is designed to supply a means for automatically restoring the type support to a position within the sphere of action of the return mechanism (where it has been carried beyond the same) during the composition of matter whose measure is in excess of the normal capacity of the primary return mechanism.

65 In the present form of embodiment of the

invention, the return latch 8 instead of being mounted upon slide 9 as heretofore, is pivotally applied to a head or link 11, Fig. 5, which is in turn pivotally connected to slide 9 by a bolt or pin 12 about which it is free to oscillate in a direction to move the latch 8 into and out of the type channel. Head 11 is pivotally connected by pin 13 with the usual yielding coupling 14 the latter connected to actuating lever 10. The arrangement is such that on the outward motion of lever 10 head 11 will be swung on pin 12 until shoulder 15 thereon engages a seat on coupling 14, thereby oscillating head 11 to withdraw latch 8 from the type channel, as indicated by full lines in Fig. 3, after which the continued movement of the lever in the same direction will translate slide 9 and, through connections not shown but corresponding to those of the prior patent referred to, communicate its motion to the line carrier. A reversal in the motion of lever 10 will oscillate head 11 in the opposite direction as indicated by dotted lines in Fig. 3, to carry the return latch 8 into the type channel, and upon contact being made between a bearing 16 on head 11 and a corresponding bearing 17 on slide 9 motion in the same direction will be communicated to said slide, latch and line carrier, to cause the latch to move longitudinally of and within the type channel and to return the line carrier to the entrance end of said channel. The partial outward movement of lever 10 for retracting latch 8 without disturbing the line carrier operates to effect the withdrawal of said latch from within the type channel. As a result of this arrangement return latch 8 is or may be normally held out of the path of the type support, and is not projected therein until the beginning of the inward or return movement of lever 10, hence it offers no obstruction to the outward travel of the type support.

Mounted upon the line transerrer 3 and preferably supported to slide in the same groove or way as the type support 5, is a head or slide 19 the lower edge of which is above the level of the lower edge of the type support 5 so as to form a space for the passage of latch 8 beneath it. Head 19 is adapted to abut against type support 5 and is provided with impelling means at all times tending to advance it toward said type support. The preferred form of impelling means shown consists of a weight 21 connected to head 19 by a cord 22, the latter passing around directing pulleys 23, carried by a bracket on the frame.

To the outer end of the frame is secured a stop or guide 24 extending in a direction transversely of the type channel, and the head 19 is furnished with a projection or shoulder 25 which passes outside of said guide when the line transerrer is advanced

to deliver a line to the galley. Head 11 carrying return latch 8 is further provided with a projection or tooth 27 in position to engage a shoulder 25 on head 19 when said head 11 is oscillated to withdraw latch 8 from the type channel, *i. e.*, during the outward movement of lever 10. Such engagement is broken when the line transerrer is advanced to discharge a line into the galley, because the head 19 is mounted on the line transerrer and moves away from the tooth 27 when the transerrer is advanced. A bracket 29 mounted upon the frame carries a stop 30 projecting in the path of head 19 and adjustable longitudinally of the type channel, said stop serving to measure and limit the inward movement of head 19 when withdrawn from engagement with guide 24 by this retraction of the line transerrer.

When the galley mechanism is at rest, as in Fig. 1, head 19 is held by weight 21 in contact with stop 30, and the type support stands near the entrance of the type channel in rear of the usual type supporting jaws 31. As the line is built up by the addition of successive type its outer end engages type support 5 and moves it outward until the line is completed. During this period latch 8 occupies its retracted position, as hereinbefore explained, while tooth 27 stands behind tooth or shoulder 25 of head 19. When, now, the galley mechanism is started into action by the closing of its driving clutch, lever 10 first completes its outward stroke, thereby effecting a corresponding movement of head 19 against the resistance of its weight, at the same time causing the engagement of the line carrier with the assembled line and its movement into registry with the galley entrance. Lever 10 is arrested in its outward position, Fig. 2, while galley blade 2 is being elevated and line transerrer advanced to deliver the line to the galley, Fig. 3. Guide 24 is located slightly to one side of tooth 27 when the latter is in its extreme outward position, as indicated in Fig. 2, and during the advance of the line transerrer, to deliver the line to the galley, head 19 is moved off said tooth, and, under the action of its weight, advances slightly inward as seen in Fig. 3 until it strikes the guide 24, so that when the line transerrer retracts, thereby withdrawing head 19 from its engagement with guide 24, said head will be immediately released, and, under the action of its weight, will be moved inward into contact with stop 30. This movement of head 19 occurs just prior to the beginning of the inward movement of lever 10 and said head engages or picks up the type support 5 and moves it inward to a point beyond latch 8, so that when lever 10 begins its inward movement and tilts head 11, as indicated by dotted lines in Fig. 3, its latch 8 will be projected

into the type channel in rear of type support 5, hence in position to engage the latter during the inner movement of slide 9.

When composing to a measure within the capacity of the galley mechanism as heretofore constructed, the auxiliary return mechanism becomes inoperative and may be detached or thrown out of action in any way. It is only when the measure exceeds the normal capacity that the auxiliary becomes available to effect the return of the type support and by so doing preserve the automatic character of the galley mechanism.

The additional members shown in the drawings and marked *x* pertain to another invention, parts of which harmonize in construction and arrangement with present invention; but inasmuch as they are not functionally involved, in the present improvements, save in the matter of adaptation, and as they form subject of a separate application Serial No. 824,179 filed March 12, 1914, no description of them has been attempted in the present case.

Having thus described my invention, what I claim as new and desire to secure by Letters Patent of the United States is,—

1. A galley mechanism for type composing machines, provided with a line assembling channel, a type support movable therein, and a returning member for said type support having a limited range of motion, and in combination therewith, an auxiliary returning mechanism operating to return the type support within the sphere of action of said returning member when carried beyond the latter.

2. The combination with a galley mechanism equipped with a line assembling channel composed in part by opposed independently movable galley blade and line transerrer, a type support movable longitudinally of the line channel, a movable line carrier, and a type support returning member of limited range, and in combination therewith, an auxiliary type support returning mechanism whose range of action extends beyond and overlaps that of the returning member and supplements the latter in effecting the automatic return of the type support when carried beyond the range of the first named returning mechanism.

3. In a galley mechanism for type composing machines, the combination of the following elements, *to-wit*: a vertically movable galley blade and a laterally movable line transerrer, forming opposed side walls of a line assembling channel; a type support movable longitudinally of the line channel on the line transerrer; a reciprocating type support returning member having a fixed path of movement; and an auxiliary type support returning member movable in a path beyond and intersecting that

of the first named or primary returning member.

4. A galley mechanism for type composing machines equipped with a line assembling channel composed in part by a movable galley blade and an opposed movable line transerrer, a movable type carrier, a movable type support, a type support returning member having a limited range of movement, and actuating devices for coupling said movable members in timed relation, and in combination therewith, an auxiliary type support returning member whose sphere of action overlaps and forms a continuation of that of the first named returning member, and means for automatically actuating said auxiliary returning member to retract the type support and place it within the sphere of action of the other returning member.

5. A galley mechanism such as described, provided with a type support movable in the line assembling channel and automatic returning means for said type support of limited range of action, and in combination therewith, auxiliary automatic return means for the type support with a range of action overlapping and forming a continuation of that of the first named returning means.

30 6. In a galley mechanism such as described provided with a line assembling channel, a line carrier and a type support movable therein, and in combination therewith, a returning means for said type support including an actuating connection, a slide and a head interposed between and pivotally connected to said connection and slide, and provided with an engaging member adapted to be projected within or withdrawn from the line channel by a change in the direction of movement of the actuating connections.

7. In a galley mechanism such as described, the combination of the following elements, to-wit: a galley blade and a line transerrer independently movable in relatively transverse directions and forming opposite walls, of a line assembling channel, a line carrier, and a type support disposed in tandem and movable longitudinally of said channel and a return means for said type support, the same including a slide, a reciprocatory driving connection, and an oscillatory head pivotally connected to said slide and connection and bearing a type support engaging member.

8. In a galley mechanism such as described provided with a line assembling channel and a line carrier and a type support disposed in tandem within and independently movable longitudinally of said channel, and in combination therewith a returning mechanism for said type support including a reciprocatory line carrier actuating slide, a head pivoted to said slide

and carrying a type support engaging member, and an actuating connection coupled with said head and operating to oscillate the latter.

9. In a galley mechanism such as described, the combination with a line assembling channel composed in part by a movable galley blade and an opposed movable line transerrer, a line carrier and a type support disposed in tandem and movable longitudinally of the type channel, and an automatic primary returning mechanism for the type support having a definite range of motion, of an auxiliary automatic type support returning mechanism whose range of action intersects and forms a prolongation of the primary returning means, said auxiliary return mechanism delivering the type support within the sphere of action of the primary returning mechanism before the latter is brought into action to effect a return of the type support.

10. The combination with a galley mechanism such as described including a movable line transerrer forming part of the wall of the line assembling channel, a movable type support and primary type support returning means, of an auxiliary type support returning means whose sphere of action intersects and extends beyond that of the primary returning means.

11. The combination with a galley mechanism equipped with a movable line transerrer forming a wall of the line assembling channel, a type support movable upon the line transerrer within said channel, and automatic returning means for said type support, of an auxiliary type support returning means including a head movably supported on the line transerrer in tandem with the type support, means for moving said head toward the type support, a fixed member located in advance of the line transerrer and adapted to engage said head when the line transerrer is moved to discharge a line into the galley, and an actuating member for said head coupled with the primary type support returning means and operating to engage and retract the head, said head being disengaged from said actuating member during the forward movement of the line transerrer and deposited upon said fixed member, to be in turn disengaged from the latter and permitted to advance toward the type support on the return movement of the line transerrer.

12. In a galley mechanism for type composing machines equipped with a line assembling channel and a type support movable longitudinally thereof and in combination therewith, a plurality of type support returning means arranged in tandem and operating successively upon the type support to return it to initial position.

13. In a galley mechanism such as de-

scribed, the combination with the line trans-
ferrer, type support and primary returning
means for said support including an oscil-
latory head carrying an engaging member,
5 of an auxiliary returning means including a
movable head disposed in tandem with the
type support on the line transerrer, an en-
gaging member coupled with the oscillatory
head of the primary returning means and
10 adapted to engage the type support, im-
pelling means for the movable head, and a
fixed guide in position to engage said mov-
able head, and temporarily arrest its move-
ment when by the advance of the line trans-
15 ferrer said movable head is withdrawn from
the engaging member of the primary return-
ing means and engaged with said fixed
guide.

14. In a galley such as described, the com-
20 bination of the following elements, to-wit; a
reciprocatory line transerrer; a type sup-
port movable in guides on the line trans-
ferrer; a type support returner mounted
25 upon an oscillatory reciprocating head, a
movable head, disposed in tandem with the
type support on the line transerrer and
provided with one way propelling means; a
fixed guide to which the movable head is
30 delivered upon the forward and withdrawn
therefrom on the reverse movement of the
line transerrer; and a stop for said movable

head so disposed as to arrest the latter when
it has retracted the type support into the
path of the first named type support re-
turner.

35

15. In a galley mechanism such as de-
scribed, the combination of the following
elements, to-wit: a reciprocatory line trans-
ferrer; a type support and an independently
movable head disposed in tandem and mov-
40 able longitudinally of the line transerrer;
means operating to constantly press said
head toward the type support; an oscilla-
tory reciprocating head provided with
means for alternately engaging the type 45
support and associated movable head to
move them in opposite directions; and a
fixed abutment for receiving said movable
head when released from said engaging
means by the advance of the line transerrer, 50
said abutment being disposed to one side of
the path of movement of the complemental
engaging surface on the movable head so as
to permit a displacement of the movable
head sufficient in degree to prevent reën- 55
gagement with the oscillatory reciprocating
head upon the return movement of the line
transerrer.
